CAN-BODY MAKER

Magnus E. Widell, Cincinnati, Ohio, assignor to
 American Can Company, New York, N. Y., a
 corporation of New Jersey

Application July 29, 1938, Serial No. 222,053

8 Claims. (Cl. 93—49)

The present invention relates to can body making machines and has particular reference to improvements in producing fibre can bodies from flat blanks which are progressively folded into can body shape in step by step stages, the side seam edges of the blank being incorporated in a side seam bonded with a thermoplastic adhesive carried on the blank and heated to a tacky bonding condition during formation of the can body.

An object of the invention is the provision of an improved can body making machine wherein flat and creased fibre blanks carrying thermoplastic adhesive along at least one side seam edge are advanced along a straight line path of travel in step by step stages through a plurality of stations at which the blank is folded by cooperating jaws and the adhesive is heated to a tacky condition in order to bond the folded side seam edges into a tight side seam.

Another object is the provision in such a machine of cooperating wing jaws operating in pairs and in synchronism so that a can body blank after being folded is guided by one pair of jaws during advancement while another pair of jaws is moving out of the way to permit entrance into the folding station of a succeeding blank thereby effecting a greatly increased speed of operation of the machine.

Another object is the provision in a machine of this character of improved devices for heating the side seam flaps of the body blank and for quickly and efficiently rendering the adhesive on the flaps into a tacky condition.

Another object is the provision in such a body maker of devices which prevent overheating of the adhesive on the blank edges so that the adhesive will not be burned when blanks remain at the heating station due to stopping of the machine.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a can body making machine embodying the instant invention, parts being broken away, the view also including a wiring diagram of the electric circuits used to impart certain operations in the machine;

Fig. 2 is a perspective view of the bed of the machine with parts removed and other parts broken away;

Fig. 3 is a longitudinal section taken substan-

tially along a vertical plane indicated by the lines 3—3 in Fig. 1;

Fig. 4 is a longitudinal elevation of a side of the machine with parts broken away;

Figs. 5 and 6 are transverse sections taken substantially along the respective lines 5—5 and 6—6 in Fig. 4;

Fig. 7 is an end elevation as viewed from the right in Fig. 4;

Fig. 8 is an enlarged perspective detail of a portion of the machine bed and certain parts concealed therein;

Fig. 9 is an enlarged longitudinal section taken through parts at the heating station of the machine, with parts broken away;

Fig. 10 is a horizontal section taken substantially along the broken line 10—10 in Fig. 9;

Fig. 11 is a sectional detail taken substantially along the line 11—11 in Fig. 10;

Fig. 12 is an enlarged sectional view taken substantially along the line 12—12 in Fig. 9;

Figs. 13, 14 and 15 are sectional details taken substantially along the respective lines 13—13, 14—14 and 15—15 in Fig. 12;

Fig. 16 is an enlarged sectional view taken substantially along the line 16—16 in Fig. 9; and

Fig. 17 is a side elevation taken substantially along a plane indicated by the line 17—17 in Fig. 16, parts being broken away and other parts being broken back.

As a preferred embodiment of the instant invention the drawings illustrate a can body making machine in which flat blanks *a* (Fig. 1) preferably of fibrous material are moved successively past a plurality of working stations which form the blanks into tubular can bodies. In the present case the can bodies are rectangular in cross section, the forming of the bodies being effected by folding or bending the blanks along creases *b* which are produced in the blanks before the latter are introduced into the body maker herein described. This creasing of the blanks forms no part of the present invention.

The creases preferably extend parallel with short edges *c*, *d* of the blank, these edges and the marginal portions adjacent them being referred to hereinafter as the side seam edges. Edge *d* carries a band of dried thermoplastic adhesive *e* which has been previously applied by mechanism not involved herein. This band *e* when heated bonds the side seam edges into a tight side seam when the edges are brought together during the body forming operations.

The creased and adhesive banded blanks *a* are introduced into the machine in any suitable

manner at a blank receiving station A (Fig. 1). The blank enters this station with its creased surface, i. e., the surface that will be the interior of the body, upward and the creases extending longitudinally of the machine. In this relative position the blank is advanced along a straight line path of travel from station to station in a step by step movement, the blank coming to a full stop at each station.

10 The first stepped movement advances the blank from the receiving station A to a notching station B. Here the corners are cut-off of the uncoated side seam edge *c* as shown at *f* in Fig. 1.

15 The next stepped movement advances the notched blank through a forming station C. At this station the blank is folded along the two inner creases *b* thereby converting the flat blank into U-shape as shown in Fig. 1.

20 While the folded blank is maintained in this U-shape it is further advanced in three stepped movements through a heating station D which includes an auxiliary folding station E. During passage of the blank through the heating station D the dried adhesive *e* on its side seam edge *d* is sufficiently melted to produce a tacky condition. The blank is also folded at the auxiliary folding station E along its outer creases *b* and its side seam portions *c, d* are brought close together in overlapping relation, but not touching, and with the tacky adhesive between them.

25 In moving out of the auxiliary folding station E the blank is advanced directly into a side seam bumping station F. Here the edges of the body are engaged by gauge fingers which longitudinally align or bring into register the overlapping side seam edges. After being aligned the seam edges are pressed tightly together in the completed side seam which thereafter holds the body together. The body forming operation being thus completed, the body is discharged from the machine to a suitable place of deposit.

30 The various operating parts of the machine are carried on a horizontal frame 11 having legs 12. One end of the frame is bolted to an upright auxiliary frame 13.

35 The step by step movement of the body blanks *a* through the machine is effected by a feeding device which includes a pair of parallel feed bars 15 (Figs. 1, 2, 5, 6 and 8). These feed bars extend throughout the full length of the machine and are provided with spaced feed dogs 16. The feed bars are carried in inverted T-shaped slideways 17 formed partially in the top of the frame 11 and partially in a plate 18 which is secured to the frame between the feed bars. The top of the plate is flush with the top of the frame and also with the top of the feed bars.

40 Each feed bar 15 is set inwardly for the greater portion of its length as best shown in Fig. 2. This brings the feed dogs in these set-in portions closer together along a transverse line so that they can better engage the blank after it has been folded along its inner creases *b* as hereinbefore explained. In like manner the slideways 17 in the frame 11 and the plate 18 are formed to properly guide these set-in portions of the feed bars.

45 The feed bars 15 are reciprocated in unison in the slideways 17. For this purpose the set-in portions of the feed bars are tied together by a spacer block 25 (Figs. 3 and 8) provided with depending lugs 26 which are connected to one end of a link 27. The opposite end of the link is connected to a rocker arm 28 (see also Figs. 1, 2, 4, 6 and 7) which is mounted on a pivot shaft 29

carried in bearings 31 formed in the auxiliary frame 13.

50 Intermediate its length the rocker arm 28 is provided with a pivot pin 35 which carries a bifurcated end of a pitman 36. The opposite end of the pitman surrounds an eccentric crank pin 37 carried in a pair of eccentric discs 38 formed as a part of a transverse crank shaft 39 journaled in bearings 41 disposed in the main frame 11. The crank shaft 39 carries a sprocket 43 which is 10 rotated by a chain 44 taking over a driving sprocket 45. The driving sprocket is mounted on a main drive shaft 47 journaled in bearings 48 formed in the auxiliary frame 13. This drive shaft is rotated by any suitable means and constitutes the 15 main source of power for operating the moving parts of the machine in synchronism.

55 Thus the main drive shaft 47 rotates the crank shaft 39 through the sprocket and chain connection and thereby rocks the arm 28 and hence 20 reciprocates the feed bars 15 connected therewith first on a forward or feeding stroke and secondly on a backward or return stroke. On the forward stroke of the feed bars the feed dogs 16 engage behind a blank *a* introduced into the machine at 25 the receiving station A and advance it one step into the notching station B as hereinbefore explained.

60 During this travel of the blank, it slides along the top of the main frame and is guided by stationary guide rails 51 (Figs. 1, 2 and 3). The blank is also prevented from vertical displacement by horizontal and longitudinal guide bars 52 which are secured to a cross-beam 53 bolted at its ends to the guide rails 51.

65 At the notching station B there is provided a cutting or notching device 55 (Figs. 1, 2 and 4) which is located at one side of the machine adjacent the path of travel of the uncoated side-seam edge *c* of the blank. The notching device 40 includes a stationary housing 56 having spaced vertically disposed gibs 57 in which a slide 58 operates. The housing is bolted to the top of the frame 11. The slide is formed with a die head 59 which when performing the notching operation is adapted to move down into a suitable die 61 seated in a recess 62 formed in the frame 11. It is these die members which cut off the corners *f* of the uncoated side seam edge *c* of the blank as hereinbefore described.

70 Movement of the slide 58 in its guideways 57 is effected by a cam groove 64 (Fig. 4) which is formed in the inner face of a combined cam and flywheel 65 carried on the main drive shaft 47. The cam groove is provided with a cam roller 55 66 (see also Fig. 6) which is carried on a lever 67 mounted at its lower end on a stud 68 secured in the auxiliary frame 13. Rotation of the flywheel therefore rocks the lever 67 in time with the other moving parts of the machine and in 60 time with the advancement of the blanks along the top of the frame 11.

75 The upper end of the lever 67 is secured to a connecting rod 71, the opposite end of which is secured to one leg of a bell crank lever 72. Lever 72 is pivotally mounted on a side of the frame 11 adjacent the notching device 55. The other leg of the bell crank lever is connected by a link 73 to an arm 74 mounted on a short shaft 75 carried in a bearing 76 (see Figs. 1 and 2) formed in the 70 notching device housing 56.

80 Adjacent the inner end of the bearing 76 the shaft 75 carries a toggle arm 78 which connects with an auxiliary toggle arm 79 disposed in a recess 81 in the die head 59. The auxiliary toggle 78

arm 79 is mounted on a pin 82 carried in the head. It is this mechanism which moves the die head 59 down into the die 61 at the proper time when a blank *a* is positioned at the station B and it is then that the corner notches *f* are produced.

The first folding operation performed on the notched blank, i. e., at the forming station C, is effected by bending its outer portions, adjacent the two inner crease lines *b*, into parallel vertical walls (Fig. 1). The blank is bent around a stationary mandrel or forming horn 91 and is thereupon U-shaped. This horn is square in cross-section when such a shape of the can body is being formed. In width therefore the horn is 10 the same dimension as the distance between the two inner creases *b* of the body blank.

The forming horn 91 is located over the top of the main frame 11 and is above the inset portions of the feed bars 15, one end of the horn 20 being adjacent the notching station B, the horn extending longitudinally of the machine throughout the remainder of its length. The horn is spaced slightly above the top surface of the frame so that a blank in being fed from the notching 25 station B into the forming station C will ride freely under the horn. Grooves 92 formed in the bottom of the horn provide clearance for the feed dogs 16.

The entrance end of the horn, i. e., the end adjacent the notching station B, is suspended from a curved bracket 93 (Figs. 1, 3 and 4) which is bolted to the main frame on one side. The horn is further suspended nearer its center from a curved bracket 95 which like bracket 93 is bolted 35 at one side to the main frame. This manner of supporting the horn leaves its discharge end free and unsupported so that the finished tubular bodies may be readily removed therefrom.

The horn is maintained at an even temperature 40 by circulating a fluid cooling medium therethrough. For this purpose the horn is provided with a pair of horizontally extending channels 101 (Fig. 3). Adjacent the horn supporting bracket 93 the lower channel communicates with a fluid inlet pipe 102 which is threaded into the 45 top of the horn. The upper channel communicates with a fluid outlet pipe 103 which is threaded into the horn adjacent the pipe 102. At the discharge end of the horn the upper and 50 lower channels are connected by a short vertical channel 104.

Bending of the blank into the initial U-shape hereinbefore mentioned is preferably done by 55 cooperating pairs of movable jaws 111, 112 (Figs. 1, 5 and 8) which fold the blank up and around the horn 91. These jaws are disposed adjacent the two opposite vertical sides of the horn and operate within an opening 113 formed in the top of the main frame 11. There is a jaw 111 and a jaw 112 on each side of the horn.

The folding jaws 111, 112 are loosely mounted 60 on a horizontal pivot shaft 115 (see also Fig. 3) which is carried in bearing blocks 116 secured to and depending from the top wall section of the main frame 11. Each jaw 111 is provided with a toggle link 118 which at its upper end is pivotally secured to the jaw. The lower ends of these two links 118 are joined and are connected to the inner end of a cam lever 121.

The lever 121 is loosely mounted on a pivot 70 shaft 122 carried in bearings 123 which depend from the top wall section of the frame 11. The outer end of the cam lever 121 carries a cam roller 125 which operates in a suitable cam groove 75 formed in a face cam 126 secured to a cam shaft

127 journaled in bearings 128 formed in the main frame 11.

In a similar manner the jaws 112 are provided with toggle links 131. These links connect with each other and are secured to the inner end of a cam lever 132. Lever 132 is mounted on the pivot shaft 122 alongside the cam lever 121. The outer end of the lever 132 carries a cam roller 133 which operates in a cam groove 134 of a face cam 135 mounted on the cam shaft 127 adjacent 10 the face cam 125.

Cam shaft 127 is continuously rotated in time with the other moving parts of the machine by a bevel gear 138 (Figs. 7 and 8) which is carried on the cam shaft. This gear meshes with a driving bevel gear 139 which is mounted on the crank 15 shaft 39. The crank shaft 39 therefore serves as a medium of power for the cam shaft.

Thus as the cam shaft 127 rotates, the face cams 126, 135 rock the cam levers 121, 132 on 20 their pivot shaft 122 and thereby, through the toggle link connection with the folding jaws, move them toward and away from the vertical side walls of the forming horn 91.

When a notched blank *a* is first advanced into 25 the folding station C both sets of folding jaws 111, 112 are in open position and below the path of travel of the blank along the top of the frame 11 as shown in Fig. 5. The blank is brought to rest over the top of the jaws and as the feed bars 15 move away from the blank on their return stroke, both sets of jaws move up simultaneously. The jaws thus engage under the blank and fold it up around the horn 91 as hereinbefore explained.

As soon as this folding operation is completed 40 the first jaws 111 immediately return to their open position within the frame opening 113 and below the path of travel of the blanks. The jaws 112 remain in raised position where they 45 hold the folded blank against the horn until its next step movement. Thus when the feed bars 15 again move on a forward stroke and bring a new blank *a* into the folding station C, while they simultaneously advance the folded blank into the 50 next station, the jaws 111 are out of the way and will not interfere with the entrance of the new blank.

It is only when the preceding folded blank is 55 well advanced into the next station, where it is retained in folded position by other elements, that the second set of jaws 112 move down within the frame opening 113. This is done in time with the advancement of the new incoming blank so that the jaws will be out of its path of travel 60 by the time it reaches them. Such cooperative action of the two sets of jaws permits quicker feeding of blanks through the machine and also permits a maximum of blank holding time.

The heating station D is disposed adjacent the 60 folding station C and accordingly the U-shaped blank when advanced from the folding station is moved directly into the heating station. During this advancement the bent up portions of the advancing blank are held in upright position against 65 the sides of the horn by guide rails 145 (Fig. 1) which are disposed adjacent the horn on both sides. These guide rails are preferably mounted on hinged frames 146 so that they may be swung out of the way when desired. The frames are 70 mounted on pivot shafts 147 carried in bearings 148 (see also Figs. 2, 4 and 6) bolted to the main frame 11.

At the heating station D there is located a heating hood 151 which overhangs the horn 91

and which receives through its upper end a heating medium such as hot air or the like from any suitable source of supply. This heating medium is directed against the upright portions of the blank in two successive stages thereby preheating them. The bottom of the hood has bolted to it a first stage heating or deflecting plate 152 (Figs. 1, 9, 10, 12 to 15) and a longitudinally co-extensive second stage heating or auxiliary deflecting plate 153 (see also Figs. 16 and 17). These deflecting plates surround and abut against the horn supporting bracket 95.

Deflecting plate 152 provides heating channels 154, 155 (see Figs. 10 and 12) through which the upright bent portions of the U-shaped blank pass as the latter is advanced along the horn for its first stage of heating. Channel 154 is set off by a transverse ceiling or arch wall 156 which merges along one side into a depending wall section 157 and along its opposite side into a depending wall section 158. Channel 155 is set off by the wall section 158, a longitudinal ceiling or rib 159, and a baffle plate 160 which is secured to the side of the rib 159.

In a similar manner the auxiliary deflecting plate 153 provides heating channels 165, 166 (see also Figs. 10 and 16) through which the blank passes for its second stage of heating. Channel 165 is set off by a transverse ceiling or arch wall 168 which merges along one side into a depending wall section 169 and along its opposite side by a thickened and curved bottom rib 170. Channel 166 is set off by the curved bottom of the rib 170 and an adjacent depending wall section 171.

Near the outer end of the auxiliary deflecting plate 153 the channel ceiling walls 168, 170 slope downwardly into a bottom wall 172 which merges into an outer end wall 173 of the plate. This end portion of the plate is divided off by inner walls 174 and is enclosed by a cover 175 thus providing a small heating chamber 176.

Hot air from the hood 151 is admitted into the heating channels 154, 155 of the deflecting plate 45 and channels 165, 166 and chamber 176 of the auxiliary deflecting plate by slide valves which are carried in the plates. Heating channel 154 is served by a slide valve 181 (Figs. 10, 12 and 15) which slides in a groove 182 formed in the depending wall section 157. The valve is provided with a plurality of vertical flutes 184 which communicate with the interior of the hood.

Under normal operation of the machine as when blanks *a* are advancing along the horn 91 the flutes 184 of the slide valve 181 are in register with spaced ports 185 which are formed in the depending wall section 157. These ports are adjacent the path of travel of the uncoated bent-up portion of the U-shaped blank *a* and thus direct 60 the heating medium against this portion of the blank as the latter advances through the heating station.

In this first preheating stage the adhesive coated bent-up portion of the advancing blank passes through the channel 155. This channel is served by a slide valve 188 which is carried in a groove 189 formed in the depending wall section 158. This valve is also provided with flutes 191 (see also Fig. 14) which register with spaced ports 192 arranged in a horizontal row and formed in the side of the wall section 158. Under normal operating conditions of the machine, the heating medium from hood 151 also passes 75 through the flutes 191 and ports 192 and thereby

impinges against the adhesive *e* on the passing blanks.

If for any reason the machine stops operating while blanks *a* are passing through the heating station provision is made for shifting the slide valves into port closing position so that the heating medium will be cut off. This prevents burning of the adhesive.

Shifting of the slide valve 181 moves its flutes into a position between the spaced ports 185 thereby completely cutting off the heat. Shifting of valve 188 also moves its flutes into a position between its spaced ports 192 so that they are closed but in this position of the flutes they come into register with a second horizontal row 15 of spaced ports 195 formed in the side of the depending wall section 158. These ports 195 direct the hot air over the top of the upright coated edge of the blank. The by-passed air strikes against the baffle plate 160 and thus escapes 20 without impinging against the adhesive *e*.

Shifting of both slide valves 181, 188 is in unison and is effected by a rack and segment connection. The valves are provided with rack teeth 196 (Figs. 14 and 15) cut in the top edges thereof. These teeth are at all times in engagement with similar teeth 197 formed in depending segment arms 198 of a shift lever 199. There are two of these segment arms 198, one for each slide valve.

The shift lever 199 is rocked only when the machine starts or stops, the lever being mounted on a pivot pin 201 carried in bearings 202 formed in opposite side walls of the hood 151. A single upright arm 203 of the lever is connected to a 35 clevis 204 of a link 205 the opposite end of which is attached to a depending leg of a bell crank lever 206.

The bell crank lever 206 is mounted on a pivot pin 207 carried in bearings 208 formed in a bracket 209 bolted to the end of the hood 151 at the left as viewed in Figs. 9 and 10. A laterally extending leg 212 of the bell crank lever is connected to the lower end of a vertically disposed movable core 213 normally held retracted within 45 a solenoid 214 mounted on a bracket 215 (Fig. 1) secured to the hood 151. The core is maintained under pressure of a compression spring located inside the solenoid, the tension of said spring tending to project the core outwardly from the 50 solenoid.

Solenoid 214 is preferably connected into a power line supplying electric energy to an electric motor which constitutes the main driving power of the machine and which drives the main 55 shaft 47, the latter being connected with the motor in any suitable manner. In the wiring diagram illustrated in Fig. 1 this electric motor is indicated by the numeral 220. One terminal of the motor is connected by a lead wire 221 to the 60 solenoid 214. The other terminal of the motor is joined by a wire 222 to a service switch or button start and stop switch 223 which in turn is connected by a wire 224 to a suitable source of electric energy such as a generator 225. The 65 generator is also connected by a wire 226 to the solenoid 214.

When the switch 223 is closed the motor circuit is complete and energy from the generator 225 excites the motor 220 which in turn rotates the 70 machine driving shaft 47. The energy flowing along the completed circuit also energizes the solenoid and this energy acting on the solenoid core 213 draws and maintains the latter in retracted position within the solenoid. Thus the 75

core, through the linkage connecting with the slide valves 181, 188 maintains the latter in their normally open position.

When the machine is stopped for any reason the motor circuit is broken and the solenoid 214 is thus deenergized. Hence the compression spring within the solenoid depresses the core 213 and thus shifts the slide valves 181, 188 into their closed position as hereinbefore described.

Returning now to the second heating stage of the U-shaped blank it should be understood that this stage of heating takes place while the blank, is passing under the auxiliary deflecting plate 153. The uncoated upright portion of the blank passing through the channel 165 (Figs. 10 and 16) is heated by hot air admitted into the channel through spaced ports 231 which are formed in the depending wall section 169 of the auxiliary deflecting plate 153. These ports register with vertical flutes 232 of a slide valve 233 when the latter is in its normal position. The flutes communicate with the hot air hood 151. This slide valve 233 is similar to the slide valve 181 and in like manner slides in a groove 234 formed in the depending wall section 169 of the auxiliary deflecting plate 153.

In similar manner the adhesive coated upright portion of the U-shaped blank passes through channel 166. Hot air is admitted into this channel by way of a slide valve 237 which slides in a groove 238 formed in the ceiling wall 170 of the auxiliary deflecting plate 153. The valve is provided with vertical holes 241 which at their upper end communicate with the hood 151. At their lower end, when the valve is in its normal position, the vertical holes 241 register with vertical spaced ports 242 formed in the bottom of the ceiling wall 170. Hot air is thus directed straight down onto the coated portion of the blank.

When the machine stops operating the slide valves 233, 237 are shifted into port closing position in unison with the two previously mentioned first stage slide valves 181, 188. Valve 233 moves into a position where its flutes 232 are between the spaced ports 231 thereby completely closing off the latter. Valve 237 also moves its holes 241 into a position between its ports 242 so that the latter are closed off.

Provision is made however for permitting the hot air to escape through the valve 237. This is effected by way of horizontal and spaced escape ports 245 (see also Fig. 17) which are formed in the outer side portion of the ceiling wall 170. These escape ports register with horizontal bores 246 which are formed in the outer side of the valve 237 and which communicate with its vertical holes 241. Hence when the valve is in closed position the heated air escapes through the side of the auxiliary deflecting plate so that the adhesive on the blank will not be burned.

Shifting of the second stage slide valves 233, 237 is done in an identical manner as described for the first stage slide valve 181, 188. This is brought about by a rock lever 251 (see also Fig. 9) which is mounted on a pivot shaft 252 carried in bearings 253 formed in opposite sides of the heating hood 151. The lever is provided with two depending segment arms 254 having rack teeth 255 which mesh with rack teeth 256 formed in the top edges of each of the valves. The rock lever 251 is also provided with a single upper arm 257 which is connected by a link 258 to the first stage link 205 and its clevis 204. The rock lever 251 and its slide valves 233, 237 thus move

in time with the lever 199 and its valves 181, 188 and is controlled by the same solenoid 214.

Near the end of the second stage of heating and while the blank is still under the hood 151, its uncoated and coated edge portions c, d are folded down over the top of the horn 91 and into overlapping relation. This is done at the auxiliary folding station E. This folding brings the U-shaped blank into the desired rectangular form of the body being produced.

The uncoated edge portion c is first folded into horizontal position. This is brought about by a stationary plate cam 261 (Fig. 1) which overhangs the horn 91 and which is secured to one of the blank guide rails 145 (see Fig. 4). The overhanging portion of the cam is formed with a sloping cam surface 262. As the blank advances along the horn it engages against the cam surface and is thereby turned down against the top of the horn (see also Fig. 16) and under the cam. This folds the blank along the adjacent outer crease line b.

After the uncoated edge portion c has thus been brought down into place, the opposite and now heated or tacky adhesive coated edge portion d is folded over at an angle along its adjacent outer crease line b (see Fig. 16). This folding is accomplished by a stationary plate cam 264 (Fig. 1) which is secured to its adjacent blank guide rail 145. The cam is provided with a cam surface 265 which overhangs the horn and which is engaged by the moving blank as it advances along the horn.

During this folding and overlapping of the blank edges c, d the blank is passing under the heating chamber 17 (Fig. 16) of the auxiliary deflecting plate 153 and is still receiving a current of hot air. The exterior surface of the angularly disposed edge portion d receives heat from the ports 242. Other ports 267 (see also Fig. 10) formed in the bottom wall 172 which encloses the heating chamber, deflect heated air under the angularly disposed edge portion d of the blank and also against the turned down edge portion c. These ports 267 are disposed at an angle in the bottom wall 172 and transmit air received in the chamber from the ports 231 adjacent the slide valve 233. This completes the heating and folding of the blank.

On the next forward movement of the feed bars 15 the heated and folded blank is advanced into the bumping station F where the side seam edges c, d are brought into longitudinal alignment and are then squeezed together in a tight side seam. This is done while the adhesive on the blank is still tacky so that a strong side seam results.

Alignment of the side seam edges is effected by a pair of swinging gauge fingers 271 (Figs. 1, 2 and 6) which are located, one on each side of the horn 91 and in close proximity thereto. Each finger is mounted on a rocker pin 272 carried in bearings 273 formed in a cross web 274 of the auxiliary frame 13. At its upper end each rocker pin carries a bevel gear 276 which meshes with a bevel gear 277 mounted on a transverse rocker shaft 278. The rocker shaft is carried in bearings 279 formed in the frame web 274.

One end of the rocker shaft 278 projects beyond the side of the auxiliary frame and carries an arm 281 having a bifurcated end 282 in which a block 283 is supported on trunnions 284. Arm 281 is yieldably connected by a link 286 to the outer end of a cam lever 287. The cam lever is carried on a pivot pin 288 secured in a

boss 289 of the auxiliary frame 13. The upper end of the link 286 extends through a hole in the block 283.

The yieldable connection is provided by a compression spring 291 which surrounds the link and which is held in place by a collar 292 on the link. The upper end of the spring abuts against the block 283 and forces it against a locknut 294 threaded on the end of the link. The arm 281 and the cam lever 281 are moved in unison by a cam roller 296 carried on the cam arm and operating in a cam groove 297 of a cam 298 mounted on the main drive shaft 47.

Thus as the cam 298 rotates, it shifts the linkage connecting with the rocker shaft 278 and hence rocks the latter and the gauge fingers 271 in time with the advancement of the blanks *a* along the horn 91. When the blank first enters the bumping station F the fingers are open or in swung back position so that they will not interfere with the passage of the blank. When the blank comes to rest at the bumping station the fingers follow in after it and engage against and push the side seam edges *c*, *d* into longitudinal register with each other so that the end of the body, produced from the blank, will be even and straight.

Hot air is blown on the heated adhesive on the blank edge *d* while the blank is at this bumping station so that the adhesive will be maintained in a tacky condition. This air is preferably received from the heating hood 151 and is conducted through a conduit 301 (Figs. 1, 4, 10 and 11) one end of which connects with the hood. 30 The opposite end widens out into a nozzle 302 which extends into close association with the angularly disposed blank edge *d* before it is bumped down.

While the side seam edges of the blank are held in register they are bumped or squeezed into tight engagement with each other. This is done by a vertically movable hammer 311 (Figs. 3 and 7) which is located over the forming horn 91 just above the angularly disposed edge portion *d* of a blank at rest on the horn. The hammer is preferably cooled by a fluid cooling medium which is circulated through a channel 312 formed therein. Circulation of the cooling medium is maintained through an inlet pipe 314 and an outlet pipe 315 threaded into the hammer and communicating with the channel.

The hammer 311 is provided with an upwardly extending stem 317 which slides in a guideway 318 formed in a housing 319 secured to the web 274 of the auxiliary frame 13. The stem is connected to a lower toggle link 321 which in turn is connected to an upper toggle link arm 322 of a bell crank lever 323. This bell crank lever is pivotally mounted on a block 324 which slides above the hammer stem 317 in the guideway 318.

The block is provided with a vertical shank 325 which extends up through a top web 326 of the auxiliary frame 13. The shank extends above the web and is held in position by a nut 327 which is threaded onto the shank end. A compression spring 328 surrounds the shank and is disposed between a collar 329 formed on the shank and the block 324 and thus maintains the latter under a desired pressure. The pressure may be changed as desired by adjustment of the nut 327.

Actuation of the hammer 311 in time with the other moving parts of the machine is effected by cam action through a train of links and levers connecting with an arm 332 of the bell crank

lever 323. The outer end of the arm is connected to a link 333 which also connects with an arm 334 of a bell crank 325. The bell crank 335 is mounted on a short shaft 337 carried in bearings 338 formed in an extension 339 of the auxiliary frame 13.

A second arm 341 of the bell crank 335 carries a cam roller 342 which operates in a cam groove 343 of a face cam 344. The cam is mounted on the main drive shaft 47.

Thus the cam 344 through the bell crank 335, the link 333 and the toggle links 321, 322 forces the hammer 311 down onto the angularly disposed edge portion *d* of the blank and presses it tightly against the opposite edge portion *c*. The heated and tacky adhesive *e* carried on the edge portion *d* thus forms a bond between the pressed together seam parts, uniting them into a tight side seam as hereinbefore explained.

During this bumping of the side seam edges 20 the horn 91 is additionally supported from below by a vertically movable anvil 351 (Fig. 3). The anvil is provided with a square shank 352 which slides in a guideway 353 formed in the frame extension 339. This shank is connected by a link 25 354 to a third arm 355 of the bell crank 335.

Accordingly when the bell crank 335 rocks, in actuating the hammer 311, it also moves the anvil upward against the bottom of the horn 91 and thus takes the thrust of the seam bumping action. This relieves the horn supporting brackets 93, 95 from bearing the full force of the seam bumping load.

Bumping of the side seam completes the forming of the blank *a* into a can body. The body 35 is thereafter pushed off the end of the horn 91 on the next stepped movement of the feed bars 15 and is discharged to any suitable place of deposit.

It is thought that the invention and many of its attendant advantages will be understood from 40 the foregoing description, and it will be apparent that various changes may be made in the form, construction and arrangement of the parts without departing from the spirit and scope of the invention or sacrificing all of its material 45 advantages, the form hereinbefore described being merely a preferred embodiment thereof.

I claim:

1. In a can body making machine, the combination of feeding devices for advancing can 50 body blanks along a predetermined path of travel through the machine, a forming horn disposed adjacent the path of travel of said blanks, co-operating pairs of movable instrumentalities located adjacent said horn on each side thereof for 55 pressing said blank against the sides of said horn, means for operating said movable instrumentalities in unison when pressing the blank against the horn and for operating them independently thereafter while the blank is advanced along 60 the horn so that one pair of instrumentalities will guide the blank during advancement while the other instrumentalities are moving back out of the way of the next following blank, and means for uniting side seam edges of the blank 65 into a side seam.

2. In a machine for making fibre can bodies from flat blanks having side seam edges one of which is provided with an adhesive, the combination of feeding devices for the blanks, a horn around which the blanks are formed, co-operating pairs of movable jaws adapted to engage under the blank and fold and press it into U-shape around the horn, devices for operating said jaws in unison when pressing the blank 75.

against the horn and for operating them independently thereafter so that one pair of jaws will retain the blank in its folded shape and guide it during its advancement while the other jaws recede out of the way of the next following unfolded blank, means for further bending the blank along its side seam edges to bring them into overlapping relation, and a bumping element for squeezing together the side seam edges of the blank so that the adhesive thereon will bond them together in a tight side seam.

3. In a machine for making fibre can bodies from flat blanks having side seam edges one of which is provided with an adhesive, a horn around which the blanks are formed, cooperating pairs of movable jaws adapted to engage under the blank and fold and press it into U-shape around the horn, means for operating said jaws in unison when pressing the blank against the horn and for operating them independently thereafter so that one pair of jaws will retain the blank in its folded shape and guide it during its advancement while the other jaws recede out of the way of the next following unfolded blank, means for further bending the blank along its side seam edges to bring them into overlapping relation, members located adjacent said horn for longitudinally aligning the bent side seam edges of the blank, and a bumping element for squeezing together the side seam edges of the blank so that the adhesive thereon will bond them together in a tight side seam.

4. In a machine for making fibre can bodies from flat blanks having side seam edges one of which is provided with a dried adhesive, the combination of feeding devices for the blanks, a horn around which the blanks are formed, cooperating pairs of movable jaws adapted to engage under the blank and fold and press it into U-shape around the horn, means for operating said jaws in unison when pressing the blank against the horn and for operating them independently thereafter so that one pair of jaws will retain the blank in its folded shape and guide it during its advancement while the other jaws recede out of the way of the next following unfolded blank, devices for heating the side seam edges of said blank to render the adhesive thereon tacky, means for further bending the blank along its side seam edges to bring them into overlapping relation, and a bumping element for squeezing together the side seam edges of the blank so that the heated and tacky adhesive thereon will bond them together in a tight side seam.

5. In a machine for making fibre can bodies from flat blanks having side seam edges one of which is provided with a thermoplastic adhesive, the combination of a forming horn, feeding devices for advancing the blanks in succession in a step by step movement along said horn, movable jaws for engaging under a blank and for bending it into U-shape around said horn, heating devices adjacent said horn for preheating the upright portions of the folded blank, which portions include the side seam edges, means for bending the heated side seam edges of the blank over the top of the horn and into overlapping

relation, and a bumping element for securing said heated seam edges together to provide a tight side seam.

6. In a machine for making fibre can bodies from flat blanks having side seam edges one of which is provided with a thermoplastic adhesive, the combination of a forming horn, feeding devices for advancing the blanks in succession in a step by step movement along said horn, movable jaws for engaging under a blank and for bending it into U-shape around said horn, heating devices adjacent said horn for preheating the upright portions of the folded blank, which portions include the side seam edges, means for bending the heated side seam edges of the blank over the top of the horn and into overlapping relation, a bumping element for securing said heated seam edges together to provide a tight side seam therealong, and devices disposed adjacent said bumping element for finally heating the adhesive on the overlapping side seam edges so that the adhesive will be in a tacky condition during the bumping operation.

7. In a machine for making fibre can bodies from flat blanks having side seam edges one of which is provided with a thermoplastic adhesive, the combination of a forming horn, feeding devices for advancing the blanks in succession in a step by step movement along said horn, movable jaws for engaging under a blank and for bending it into U-shape around said horn, heating devices adjacent said horn for preheating the upright portions of the folded blank, which portions include the side seam edges, means for bending the heated side seam edges of the blank over the top of the horn and into overlapping relation, devices for cutting off the heat from said heating devices when the machine stops operating so that the adhesive will not be burned on blanks left under said heating devices, and a bumping element for securing said heated seam edges together to provide a tight side seam.

8. In a machine for making fibre can bodies from flat blanks having side seam edges one of which is provided with a thermoplastic adhesive, the combination of feeding devices for the blanks, instrumentalities for bending said blank into a U-shape, a heating hood disposed over the path of travel of said blanks, heat deflecting devices adjacent the bottom of said hood and having longitudinal channels through which the upright portions including the side seam edges pass while being advanced, slide valves in said deflecting devices and movable into register with ports also in said deflecting devices for directing heat from said heating hood against the side seam edges of said advancing blank to preheat the edges and to bring adhesive into a tacky condition, means for shifting said slide valves into port closing position when the machine stops operating and for reshifting said valves into port opening position when the machine is in operation, devices for bending the heated side seam edges into overlapping relation, and a bumping element for securing said overlapped edges together to produce a side seam tightly bonded by the tacky adhesive.

MAGNUS E. WIDELL.
